UNITED STATES PATENT OFFICE.

ARTHUR M. KING, OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 5,640, dated March 12, 1872.

To all whom it may concern :

Be it known that I, ARTHUR MAZEPPA KING, of Kidderminster, county of Worcester, England, have invented a new and original Design for Carpets; and I do hereby declare that the following is a full, clear, and exact description thereof, which will enable others skilled in the art to make and use the same, reference being had to the accompanying photographic illustration, forming part of the specification.

This invention relates to a new design of a circular figure, A, with projecting loop *a*, and contained within a squared zigzag border, B, the new design of said zigzag border embracing

alternately oblique rectangular figures *b b*, and to a new design of a square figure, C, with scalloped borders, as shown.

I claim as my invention—

1. The design of the figure A, as shown.
2. The design of the zigzag border B, as shown.
3. The design of the figure C, as shown.
4. The design for a carpet containing the figures A C and border B, as shown.

ARTHUR MAZEPPA KING.
